UNITED STATES PATENT OFFICE.

RICHARD M. HOE, OF NEW YORK, (MARY S. HOE EXECUTRIX OF SAID RICHARD M. HOE, DECEASED,) AND DOMINICK WECKERLIN, OF BROOKLYN, ASSIGNEES, BY DIRECT AND MESNE ASSIGNMENTS, TO ROBERT HOE, PETER S. HOE, STEPHEN D. TUCKER, AND THEODORE H. MEAD, OF NEW YORK, N. Y.

INKING APPARATUS FOR PRINTING-MACHINES.

SPECIFICATION forming part of Letters Patent No. 388,680, dated August 28, 1883.

Application filed November 23, 1882. Serial No. 77,479. (No model, and the drawings are explanatory.)

To all whom it may concern:

Be it known that we, RICHARD M. HOE and DOMINICK WECKERLIN, citizens of the United States, I, the said HOE, residing in the city of New York, county of New York, and State of New York, and I, the said WECKERLIN, residing in the city of Brooklyn, county of Kings, and State of New York, have jointly invented certain new and useful Improvements in Ink-
ing Apparatus for Printing-Machines, fully described and represented in the following specification and the accompanying drawings, forming a part of the same.

In said drawings, Figure 1 is a right-hand side elevation of so much of a printing-press as is requisite to illustrate the structure and operation of the present improvements. Fig. 2 is a similar view taken from the opposite side of the machine. Fig. 3 is a longitudinal sectional elevation. Fig. 4 is a plan or top view; Fig. 5, an end elevation; and Fig. 6 a side elevation (reduced in scale) showing the inking mechanism in its two positions, one of which is indicated by dotted lines.

This invention relates to flat-bed printing-machines; and it consists in an ink-distributing apparatus arranged to distribute ink in two separate courses to independent sets of form-rollers that apply it directly to the form without the use of a distributing-table.

It also consists in mounting all of the ink-distributing apparatus in a movable carriage and providing said carriage with means for raising and lowering the same and for transferring it from and to the printing position, whereby the said apparatus is rendered capable of being removed from its operative position in front of the impression-cylinder, so as to expose the form-rollers and enable the same to be removed and replaced with great facility and convenience.

In the drawings of this invention only so much of the printing-machine is shown as is necessary to illustrate the structure of the inking apparatus and its co-operative relation to the printing-machine.

As will be readily understood, the ink-distributing apparatus is located in front of the

impression-cylinder 50, as is common. It consists of an ink-fountain, 10, in which revolves 50 a metal fountain-roller, 11, the supply of ink to which is controlled by the usual doctor-knife, 12. The ink is transferred from this fountain-roller 11 to a continuously-revolving metallic distributing-roller, 14, by an oscillating composition taking-roller, 13. The ink thus transferred is distributed upon the roller 14 by a composition riding-roller, 15. From this distributing-roller 14 the ink is transferred by a composition taking-roller, 16, to a large metallic distributing-cylinder, 17. Upon this distributing-cylinder are mounted three riding composition rollers, 18, 19, and 20, the two former of which vibrate endwise and which serve to distribute the ink evenly over the surface of the said cylinder 17. The distributed ink from the surface of this cylinder 17 is carried to separate vibrating steel distributing rollers 21 22 by means of two intermediate composition rollers, 23 24, placed at opposite sides of the cylinder 17 and resting, respectively, upon the distributing-rollers 21 22.

The distributing-roller 21 runs in contact with two form-rollers, 25 26, and the distributing-roller 22 runs in contact with two form-rollers, 27 28, which form-rollers 25 26 27 28 are mounted in adjustable bearings that are supported by brackets 106, one on each side of the machine, which brackets are secured to the main frame-work by bolts. These bearings are arranged to provide adjustments in all directions, as is common, whereby the rollers are adjusted to deposit and distribute ink upon the form as it passes in contact with their under surfaces in its reciprocatory movements. One of these brackets also supports bearings for pinions 95 96 97, which gear with the usual driving-rack on the reciprocating-bed of the machine. The pinion 95 gears with a pinion, 98, on the shaft of roller 21. Pinion 97 gears with a pinion, 99, on the shaft of roller 22, and pinion 96 gears with an intermediate, 66, that engages with another intermediate, 67, that meshes with a toothed wheel, 68, on the shaft of the cylinder 17. The two steel rollers 21 22 and the central cylinder, 17, are thus driven

by motion derived from a rack on the reciprocating type-bed, so that they and all the rollers in contact with them run forward and backward in unison with the type-bed, during which movements the inking-cylinder gives a supply of ink through the rollers 23 24 to each pair 25 26 and 27 28 of the form-rollers.

All the parts of the inking apparatus except the form-rollers 25 26 27 28 and the pinions 95 96 97 are mounted in a movable carriage, so that said parts may be bodily removed from over the form-rollers, as shown in dotted lines in Fig. 6. This frame-work 15 consists of opposite side frames, 101 102, and suitable connecting-braces, in which side frames the various rotating parts are suitably journaled, as are the pinions 66 67.

The fountain-roller 11 is given an intermittent feed through a toothed segment-pawl, and ratchet by means of a bell-crank, 80, that is connected with a rocking lever, 81, by a rod, 82, which lever 81 is vibrated at proper intervals by means of a push-rod, 83, that is operated by a cam, 30, on a longitudinal rotating shaft, 84, in the usual manner.

The roller 13 is vibrated in one direction by a bell-crank, 85, connecting-rod 86, and lever 87, which latter is vibrated by a push-rod, 88, 30 that is operated by a cam, 31, on the shaft 84, and is vibrated in the opposite direction by the spring-seated rod 35, attached to the rock-arm 36. The roller 16 is vibrated in one direction by a bell-crank, 89, rod 90, and lever 91, which latter is vibrated by a push-rod, 92, actuated by a cam, 32, on said shaft 84 and is vibrated in the opposite direction by the spring-seated rod 37. The distributing-roller 14 is driven by a belt running from the pulley 40 103 to another upon any suitable shaft of the printing-machine, and said roller is given a vibrating motion endwise by means of a right-and-left-hand worm, 51, at one end of its shaft, which worm works with an oscillating fork in the well-known manner. The rollers 18 19 21 45 22 are caused to vibrate endwise by means of rock-arms 52 53 54 55, motion being derived from a rock-shaft, 56, through cross-heads whose arms 57 58 have pins that enter grooved 50 collars on the shaft of the rollers 21 22. The rock-shaft 56 is operated through an arm, 33, which projects from its lower end and engages with a grooved cam, 34, on the shaft 84. This arrangement of inking apparatus is such that 55 it operates to distribute the ink very finely and that each pair of form-rollers receive from the large central cylinder the same quantity of ink, and as they give off the ink to the form it is constantly renewed and equalized, the result being that every part of the form is equally inked.

The ink supplying, carrying, distributing, and conveying rollers are supported in a movable carriage, so that they may, as already stated, be bodily removed from over the form-rollers that the latter may be more easily put

in place and removed and convenient access to the impression-cylinder afforded for the purpose of "making ready" its printing-surface, and this carriage is removed in the following manner: A shaft, 60, is journaled in the frame-work and runs across the lower part of the machine. It is supplied with a hand-lever, 61, at one end and at appropriate points within and near each side frame 70 with cams 62, which cams operate the T-shaped push-bars 63, the upper ends of which stand just underneath projections of the feet 42 of the movable carriage, by the operation of which push-bars the carriage, 75 when loosened from its swinging clamps 46 and clamp-screws 44, may be raised a short distance. In being thus raised the gearing that drives the various rollers separates, the grooved collars on the shafts of the rollers 21 85 22 lift off the pins in the arms 57 58 of the cross-head, and the levers of the fountain and taking rollers leave their push-rods. When the movable carriage is thus raised, a roller-frame, 40, is laid on each top rail, 41, 90 of the machine, one at each side, which roller-frames are then run in under the raised carriage, as in Fig. 6, one such roller-frame then underlying each of the feet 42 of the carriage. The top rail, 41, and the bottom of the feet 95 42 are each grooved to receive the guiding-flanges on the rollers of the said roller-frame, so that when the carriage is lowered onto the roller-frame by a contrary movement of the hand-lever 61 it will be supported in a condition to be easily rolled back and forth. When rolled back, as shown in dotted lines of Fig. 6, it will leave the form-rollers uncovered and give free access to the impression-cylinder, and will also permit the form-rollers to 105 be removed, if desired.

To bring the ink-distributing apparatus into a proper position over the form-rollers to commence the printing operation, it is rolled forward into the position shown in full 110 lines in Fig. 6. It is then slightly raised to free the roller-frames 40, the latter are rolled rearward from beneath the feet 42, and the said ink-distributing apparatus is lowered by a proper movement of the hand-lever 61 until its said feet 42 rest on the side frames of the machine, as in Figs. 1, 2, 3, and 5, when 115 its gearing will be re-engaged, the grooved collars on the rollers 21 22 will drop on the pins in the levers 57 58, and the levers 81 120 87 91 will again rest upon their push-rods 83 88 92. In this position the ink-distributing apparatus rests solidly in place, and is rigidly secured to brackets 111 and 112, projecting from the main frame of the machine, 125 by means of the projecting portions of its side frames, 101 102, which carry clamp-screws 44, the shanks of which enter sockets in brackets 111 112. (See Fig. 6.) When lowered in place, these clamp-screws 44 secure the side 130 frames to the brackets 111 112, the feet 42 being secured at the front and rear on op-

posite sides of the machine to the side frame by means of swinging clamps 46, in the manner shown in Figs. 5 and 2.

What is claimed as new is—

5. The combination, with the main frame of the printing-machine, of the ink-distributing apparatus and its vertically-movable horizontally-sliding supporting-carriage, substantially as described.
10. 2. The combination, with the ink-distributing apparatus and its movable supporting-carriage, of the independent roller-frames 40, substantially as described.
15. 3. The combination, with the ink-distributing apparatus, its movable supporting-carriage, and its elevating mechanism, of the independent roller-frames 40, substantially as described.
20. 4. The combination, with the main frame of the printing-machine, of the ink-distributing apparatus, its vertically-movable horizontally-sliding supporting-carriage, and clamp-

ing devices, substantially as described, for rigidly supporting said ink-distributing apparatus and its carriage in its adjusted position 25 during the printing operation.

5. The combination, with the movable ink-distributing-apparatus, carriage, and the devices supported by said carriage for actuating the vibrating inking-rolls, of the lifting-rods 30 83, 92, 88, mounted in the printing-machine frame, substantially as described.

In testimony whereof we have hereunto set our hands in the presence of two subscribing witnesses.
